UNITED STATES PATENT OFFICE.

CHARLES W. LEE, OF BROOKLYN, NEW YORK, ASSIGNOR OF ONE-FOURTH TO FRED-
ERICK S. BARTRAM, OF BROOKLYN, NEW YORK.

VALVE-CONTROLLING MECHANISM.

Application filed April 9, 1923. Serial No. 631,043.

To all whom it may concern:

Be it known that I, CHARLES W. LEE, a citizen of the United States, residing at Brooklyn, in the county of Kings and State of New York, have invented new and useful Improvements in Valve-Controlling Mechanism, of which the following is a specification.

This invention relates to valve controlling mechanism for internal combustion engines and has for its primary object the provision of a mechanism of this character for advancing and retarding the action of the valves of an engine of this type.

10 A further object of the invention is to provide valve controlling mechanism which can be quickly regulated to actuate the valves of the engine according to the speed of operation of the latter. Internal combustion engines are generally provided with valves which cannot be properly controlled in operation of the engine. The valves are designed to solely operate in accordance with a fixed or determined speed of the engine. As the speed is increased the valves operate out of time with the engine and in consequence thereof, considerable power is lost and when the speed of the engine is lowered below a fixed point, the valves work ahead of time which results in back firing and loss of power. My controlling mechanism may be used upon all types of internal combustion engines and is especially useful upon 20 the engines of airplanes where the valves are set for speed in the air and are too far ahead for safety and easy launching of the machine. When used in connection with airplane engines, the mechanism is designed to 30 be operated by hand from the pilot's seat or same may be automatically controlled by a governor or other means for advancing the action of the valves as the speed of operation of the engine increases and to retard the action of the valves as the speed of the engine diminishes.

35 A still further object of the invention is to provide mechanism of this character which will be simple of construction, positive of action and capable of attachment to engines of well-known makes.

With these and other objects in view, the invention resides in certain novel construc-

tion and combination and arrangement of parts, the essential features of which are 55 hercinafter fully described, are particularly pointed out in the appended claim, and are illustrated in the accompanying drawing, in which:—

Figure 1 is a view in side elevation with parts broken away of the mechanism applied to the cam and crank shafts respectively of an engine of the internal combustion type.

Figure 2 is a section on line 2—2 of Figure 1.

In carrying the invention into practice, I employ two gears 8 and 10 respectively each having its teeth cut at an angle to its axis. In effect these are spiral gears. The gear 10 is secured to the crank shaft 5 of the engine and the width of this gear is considerably greater than that of the mating intermeshing gear 8. The gear 8 is keyed at 9 to slide on the cam shaft 6 of the engine and to rotate therewith.

When the gear 8 is moved toward the right side B' of the gear 10, the mechanism is operated to retard the action of the engine valves and cause the valves to open slightly later than when said gear 8 is in a central position with respect to the mating gear 10. When the gear 8 is moved toward the left side A of the gear 10, the valves of the engine are opened sooner than they would be were said gear 8 positioned at any other point with respect to the ends of said gear 10.

In order to permit of adjustments in a longitudinal direction of the gear 8 so that it may operatively traverse the wide gear 10, I employ a rocking yoke 9' and co-acting collar 11, the latter associated with the grooved hub 12 of the relatively narrow gear 8. This disposes the yoke in a forward position on the cam shaft and movements may be imparted to this yoke through a connection 13 that can be either manually adjusted or automatically adjusted through the action of any suitable well-known form of governor. When connected with a governor the valves of the engine will be automatically actuated in timed order with the speed of operation of the engine. If desired, it obviously follows that the actuating yoke 9' may be positioned slightly in back 105 of the gears 8 and 10.

From the nature of the device and structural design, it follows that the valves of the engine can be tuned in operative synchronism with varying speeds of operation of the engine so as to positively prevent back firing; loss of power and permit the valves to be properly regulated while the engine is in operation. As stated, the device may be used in connection with all types of internal combustion engines and through its structural and functional design, is especially desirable for use in connection with airplane engines and affords means to govern the action of the valves to the proper extent either in launching the machine or when same is in flight.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my

invention limited only by the appended 25 claim.

What is claimed as new is:—

A mechanism for controlling the action of the valves of an internal combustion engine while the latter is in operation and in operative time with the speed of the engine, a gear splined to the cam shaft of the engine, a grooved hub laterally formed on the gear, a collar surrounding the hub and arranged in the groove, studs extending from diametrically opposite sides of the collar, a yoke pivotally secured at its lower end and provided with openings receiving the studs whereby movement of the yoke on its pivot will slide the gear upon the shaft through the medium of the collar and grooved hub, a gear keyed to the crank shaft of the engine and meshing with the splined gear and manually operated means secured to the upper end of the yoke. 40 45

In testimony whereof I have affixed my signature.

CHARLES W. LEE.
